No. 92,985.

PATENTED JULY 27, 1869.

T. McKINLEY.
PLASTERING MACHINE.

United States Patent Office.

THOMAS MCKINLEY, OF NEW YORK, N. Y.

Letters Patent No. 92,985, dated July 27, 1869.

IMPROVED PLASTERING-MACHINE.

The Schedule referred to in these Letters Patent and making part of the same.

To all whom it may concern:

Be it known that I, THOMAS MCKINLEY, of New York, in the county of New York, and State of New York, have invented a new and useful Improvement in Plastering-Machines; and I do hereby declare that the following is a full, clear, and exact description thereof, which will enable others skilled in the art to make and use the same, reference being had to the accompanying drawings, forming part of this specification.

This invention relates to a new and improved method of plastering, whereby the tedious and expensive operation of covering walls and ceilings of buildings with mortar is greatly facilitated; and

It consists in moving over the floor of the room where the plastering is to be done, a machine, (resting on wheels,) consisting of a box containing the mortar, with a piston to fit the box, which piston is forced upward by means of gearing actuated by the supporting-wheels, the mortar being forced from the box by the piston in a thin sheet, and pressed upon the lathing, or wall as by a trowel, as will be herein-after more fully described.

In the accompanying plate of drawings—

Figure 1 represents a top view of the machine.

Figure 2 is a vertical section of the machine through the line *x x* of fig. 1.

Figure 3 is an outside view, showing the box and a portion of the gearing.

Figure 4 is a view of the bottom of the machine.

Figure 5 is a top view of the delivery-tube or trowel.

Figure 6 is a view of a tube for forming cornice.

Similar letters of reference indicate corresponding parts.

A is the box, into which the mortar is introduced through the slide-door aperture *B*, on to the piston *C*.

This piston is raised by means of the screw *D*, which engages with a screw-thread in the tube *E*, which tube covers and protects the screw from contact with the mortar.

The screw is revolved by means of the gear-wheel *f* on its lower end, which is connected by other gear-wheels, *g* and *h*, with the gear-wheel *i*, which couples with the traction-wheel *J* of the machine.

K, *L*, and *M* represent the other three traction-wheels.

n is the pin by which the gear-wheel *i* is coupled with the wheel *J*.

This pin may be withdrawn or connected with the wheel at the pleasure of the operator.

It is not intended, as a general thing, that the machine shall deliver mortar except when passing in one direction across the floor; therefore the machine is not turned around on the reverse motion, but the gear is uncoupled, and the machine drawn back; but

I do not confine myself to this method of operating the machine.

Neither do I confine myself to operating the machine on the floor of the room. It may be operated from a scaffold, if deemed advisable, although one object which I have in view is to avoid the trouble and expense of building scaffolds, for plastering the ceilings and upper portion of the walls of buildings.

It will be seen that the upper portion of the box *A* is conical or pyramidal in form, to the top of which the tube *O* is attached, into which the tube *E* of the piston rises, as the piston is forced up, and through which the mortar is forced into the trowel or delivery-tube *R*.

The tube *R* is reduced in size and form to a broad narrow slot, as seen at *S* in the drawing, with a projecting lip, *T*, on its lower portion, which receives the mortar, and presses it to the wall or ceiling, as seen in fig. 2, when the machine is moving in the direction indicated by the arrow.

To compensate for any variations in the surface of the ceiling, or floor or staging, the delivery-tube or trowel *R* may be made elastic by means of a spring, as seen at *u*, or in any other manner.

It will be seen that some provision of this kind would be necessary, in case the ceiling and the floor or scaffold on which the machine is operated should not be exactly parallel with each other.

The delivering-tubes *R* are placed on the tube *O*, as seen in fig. 2, where they may be secured in any suitable manner.

These delivery-tubes or trowels may be in any form, so as to deliver the mortar or plaster for a smooth wall, or for ceilings, or for cornices, the tube seen in fig. 6 being designed for the latter purpose; but any design or pattern may be employed for this or similar purposes.

V represents the axles to which the driving or traction-wheels are attached.

W is a crank, attached to the gear-wheel *h*, by means of which the piston is returned to the bottom of the box, by reversing the screw.

I do not confine myself to any particular size or form of machine, nor to any particular details, as regards the construction of the machine or method of operating the piston.

Having thus described my invention,

I claim as new, and desire to secure by Letters Patent—

The box *A*, piston *C*, tube *O*, and delivery-tube *R*, arranged to operate substantially as herein shown and described, for the purpose specified.

THOMAS MCKINLEY.
